UNITED STATES PATENT OFFICE.

NATHAN FRIEDBERGER, OF PARIS, FRANCE.

HAND-MADE EMBROIDERY.

No. 839,377.

Specification of Letters Patent.

Patented Dec. 25, 1906.

Application filed April 17, 1906. Serial No. 312,117.

To all whom it may concern:

Be it known that I, NATHAN FRIEDBERGER, merchant, residing at Paris, 43 Boulevard Malesherbes, France, have invented new and useful Improvements in Hand-Made Embroidery, of which the following is a specification.

The present invention relates to a new article of manufacture, and has for its object to simplify the production of hand-made embroidery by loosely attaching to the surface of a base material with compact meshes long parallel-running threads which may be fastened at suitable points to the base material by means of the threads of the weft or in some other convenient manner, and the threads which form the embroidery-pattern are threaded either over or under these loosely-attached threads, as the case may be, in practically the same way as in darning.

Reference is to be had to the accompanying drawings, in which—

Figure 1 is a view of the base material with a part of the pattern, and Fig. 2 is an illustration of the base material with the loosely-attached parallel threads on the surface of the same.

a is a base material. This is close-meshed, and on the surface of the same are placed parallel to one another the threads *c*, loosely laid on and only attached at intervals by the weft-threads *b* of the base material *a* or in any other suitable manner. These loose threads *c* serve to hold the pattern-threads *d*, which, as is customary in darning, are passed

according to requirements, either under or over the loose threads *c*, so that the pattern-threads which lie next to each other, are passed alternately either under or over the loose threads or also by skipping several weft-threads are fixed on the surface of the material. The loose parallel threads can also be formed of the warp itself and can be of any desired thickness and color.

My improved article has the advantage of being easy to produce. The embroidering is easy and simple to perform, the loose parallel threads materially simplifying the drawing of the pattern-threads under and over the same.

What I claim as new and of my invention, and desire to secure by Letters Patent, is—

1. Hand-made embroidery which consists of a base material with close meshes, parallel threads on said base material and pattern-threads extending under and over said parallel threads as is customary in darning.

2. Hand-made embroidery comprising a base material, parallel threads on said base material secured thereto at intervals, and pattern-threads attached to said parallel threads.

In testimony that I claim the foregoing as my invention I have signed my name, in presence of two witnesses, this 3d day of April, 1906.

NATHAN FRIEDBERGER.
